(57) **CLAIM**

The ornamental design for a USB memory device as shown and described.

DESCRIPTION

FIG. 1 is a top view of the USB memory device with the lid in a closed position.

FIG. 2 is a bottom view of the USB memory device with the lid in a closed position.

FIG. 3 is a front view of the USB memory device with the lid in a closed position.

FIG. 4 is a rear view of the USB memory device with the lid in a closed position.

FIG. 5 is a right side view of the USB memory device with the lid in a closed position.

FIG. 6 is a front, top, right side perspective view of the USB memory device with the lid in a closed position; and, FIG. 7 is a rear, top, right side perspective of the USB memory device with the lid in an open position.

The portions of the USB memory device shown in broken lines form no part of the claimed design.

1 Claim, 3 Drawing Sheets
